UNITED STATES PATENT OFFICE

MATTHEW M. FRIEDEMANN, OF NEW YORK, N. Y.

DISPLAY STAND

Application filed February 8, 1929. Serial No. 338,384.

This invention relates to display stands; more particularly to display stands which may be associated with show cases. It is an object of my invention to provide a display stand which may be readily assembled and particularly associated with present existing devices, such as show cases, to thereby increase the display area.

It is contemplated by my invention to provide a display stand which is self-sustaining insofar as it may individually and by a single standard support a display shelf or a series of superimposed display shelves upon any supporting area, particularly upon a show case, without interfering with the accessibility of the member upon which it is supported, such as a show case, and at the same time serving to enhance the general appearance of the member upon which it is supported, such as the show case, in addition to supplying maximum display area, with minimum obstruction. Still further objects of my invention reside in the provision of a display stand which may be readily supplied to a supporting base, such as a show case, particularly of the character which includes glass sides and thin supporting frames, the display stand being capable of being associated with this type of show case without detracting from the display area of the show case, and which may be readily and quickly attached thereto without danger of injuring, breaking or marring any of the fragile parts of the existing show case. It is contemplated by my invention to provide a self-sustaining single standard display stand which may be associated with a show case and rigidly supported thereon, and conveniently attached, the device including attaching and supporting base mounting means capable of overcoming the difficulty incident to the irregularities of composite structures, such as frames and glasses of show cases.

Still further objects of my invention reside in the provision of a self-sustaining, single standard display device which may be adjusted to any desired stability, occasioned by the increased number of display shelves or sizes thereof, supported from the

standard and which may be additionally adjusted to take care of irregularities in the supporting area, such as a show case. It is still further contemplated by my invention to provide a display shelf which may be attached to a supporting area, such as a show case, without in any way interfering with the accessibility of this device, and which may include means for illuminating the same conveniently and supply the necessary wire connections without detracting from the appearance or in any way requiring modification of the supporting area.

Still further objects of my invention include the provision of mounting means for a self-sustaining single standard display device which may be economically assembled or knocked down for storage, packing or shipping purposes and which may be modified to provide increased stability for modification of the display area or otherwise range its size and proportions, presenting an attractive as well as utile device.

To attain these objects and such further objects as may appear herein or be herein-after pointed out, I make reference to the accompanying drawings, forming a part hereof, in which—

Figure 1 is a perspective view showing my device associated with a show case; 80

Figure 2 is a fragmentary view taken on the line 2—2 of Figure 1;

Figure 3 is a fragmentary view taken on the line 3—3 of Figure 2;

Figure 4 is a fragmentary plan view similar to Figure 2, of another embodiment of my invention;

Figure 5 is a section taken on the line 5—5 of Figure 4;

Figure 6 is a fragmentary, perspective view of a detail of the base shown in Figure 4;

Figure 7 is a perspective view of another embodiment of my device;

Figure 8 is a section taken on the line 8—8 of Figure 7;

Figure 9 is a section taken on the line 9—9 of Figure 8;

Figure 10 is a view similar to Figure 8, of another embodiment of my invention.

Making reference to the drawings, my device takes its preferred form as a display stand having a single standard 10, preferably provided with a plurality of brackets 11, arranged to hold display shelves 12, such as glass, against independent tilting action, by a single bracket support. These are arranged to be attached to the standard by key hole slot and plug engagement with 10 the key holes 13 provided to each face of the standard. The standard is preferably arranged to be supported upon a supporting area, such as a show case 14, in order that the display area of this member may be increased without interfering with the vision of a sales clerk, and without in any way detracting from the appearance of the show case. For this purpose, I provide the base engaging clamp 15, comprising complementary sections 16 and 17, frontally and rearwardly, respectively, both cooperating to embrace the standard 10 and to conform in general to the cross section of the standard. These complementary sections are preferably jointed by the screw 18 and wing nut 19, passing through an orifice 20 and an elongated slot 21. The rearward section 17 is preferably formed with a set off channel 22, substantially centrally thereof, and extended wings 23. On these wings I provide a plurality of orifices 24, preferably in stepped relation, through which the screws or similar fastening elements 25 are inserted to attach or affix the same to the frame 26 of the show case. It will be observed that by the construction described, a standard and its display elements or shelves may be quickly and conveniently attached to a show case with any thickness of frame 26, without interfering with the sliding door 27, usually provided in such devices, the orifices 24 facilitating not only attachment but adjustment to take care of the depth and thickness of the frame 26. The structure described serves to independently support a display device of the character described against forward or lateral tilting, without in any way detracting from the appearance of the show case to which it is attached when it is so used, or without preventing the general use of the show case. The side wings 23 not only give sufficient stability for the intended purpose but they act as a forward stop, as will appear more clearly as this description proceeds.

In addition, also, I may provide at the top of the standard 10, an illuminating fixture 28 and this is affixed in position by an adapter 29, which, in the present instance, is square, conforming to the general cross section of the standard. I may include conductors or leads to supply the electrical current for the fixture exteriorly of the device, beginning adjacent the adapter 29. Preferably, however, the standard 10 is made of comple-

mental sections 10a, to provide a hollow tube, and this is arranged in aligned position with the adapter 29. The conductors or wires 30 are then led through this hollow tubular member downwardly, as shown, extending 70 immediately adjacent the plate 17, directly beneath the central channel 22, serving to offset the standard 10 beyond the rear edge 31 of the show case, thus providing a clearance portion for the lead wires 30.

In the embodiment shown in Figures 1, 2 and 3 I have described my display fixtures as capable of being directly attached to a show case. For additionally stabilizing the support of the standard 10, frontally and laterally, and for additional purposes as will appear as this description proceeds, I interchange for the frontal section 16 the base 16a. This member preferably comprises laterally and frontally disposed legs 32 and 33, respectively, arranged in the preferred form in substantially right angles to each other. Centrally of this base I provide a channel 34 of the same size and shape as the frontal section 16 whereby the standard 10 may be disposed thereon. The standard 10 may therefore be rigidly disposed between the front section base 16a and the plate 17, joined to each other by the fastening elements 35, having screw engagement in the orifices 36 in the base 16a. These fastening elements may be substituted, if desired, for the bolt and wing nuts previously referred to in the embodiment illustrated in Figures 1, 2 and 3. The lateral legs 32 and 33 may be used as described and be supported upon a show case 14, and where the same is level throughout, serve to augment the lateral and frontal support provided by the plate 17. If desired, the fastening elements 25 may be omitted and the base 16a itself serve to support the standard 10 in its upright position. In this event, the back plate 17 attached to the base 16a serves as a rearward stop for the display device, preventing forward sliding movement when assembled with a display element such as a show case 14. In its preferred form, however, particularly where the show case 14 has its top provided with a glass plate 14a at a substantially lower layer 115 than the upper rail 14b, for purposes of leveling the entire device in the supporting position, it is preferred that the legs, such as 32 and 33, be provided at their under-surface with a channel 37, longitudinally of the respective branches. This is more clearly shown in Figure 6. Within this channel 37, there is housed an extension member 38, arranged for sliding relation with the leg 32 by the set screw 39, engaging the extension in an elongated slot 40. Frontally of this extension member 38, I dispose leveling members 41, which preferably include a rubber base or rubber suction cup 42, arranged to be attached to the member 38 by a screw 43.

threaded member 43. The leveling members 41, as disposed from the extension 38, may either be affixed completely within the channel 37 or else be distended outwardly beyond the legs 32 or 33, within which they are supported to the fullest extent of the slot 40. The leveling member 41, disposed within the leg 33, may be adjusted upon the plate 14a to vertically dispose the standard 10 so that though support is had upon the surface 14a, these may be adjusted to produce the desired position of the standard 10. Furthermore, particularly when the standard is disposed on a show case whose top 14 is made of glass, the suction cups formed on the bottom of the members 41 serve not only to cushion the device but also to prevent accidental displacement. As in the embodiment described in Figures 1, 2 and 3, the plate 17 may be affixed to the frame 26 with similar results, augmented by the stabilizing features of the laterally and frontally disposed legs and the leveling members included thereby.

In Figures 7, 8 and 9, I have illustrated another embodiment of my invention wherein there is interchanged for the frontal section 16 a base generally referred to as 16b. The standard and display shelf elements as previously described and illustrated may have associated with the rear plate 17, the frontal base member 16b, cooperating with the plate 17 to vertically dispose the display shelf. In its preferred form, the base 16b comprises lateral legs 32a and frontal legs 33a. It is preferred that this entire assembly be made of metal stampings or bent metal straps of substantially the same thickness and depth, capable of being knocked down for storage or shipping purposes and made from single stock material to provide maximum manufacturing economy. The base in this embodiment preferably comprises a continuous strap 44, centrally provided with an offset portion 45 to which, immediately adjacent thereto and frontally, I dispose two angle sections 46, and a front strap 47. The angle member 46 is preferably slotted for a portion of its length at 48 to permit relative adjustability for purposes which will appear.

To the outside of the strap 47, there is provided the short plate 49, carrying at its inner end the inwardly turned lip 50, capable of forming a hinged joint. The strap 44, angle 46, front strap 47 and plate 49 are all fixedly engaged by the bolts 51, passing through respective orifices formed through each of the members, thus associating the members rigidly together. It will be observed that the strap 44 and front strap 47 are spaced from each other by the thickness of the angle members 46. Disposed therebetween and beyond the edge 52 of this angle member, there is positioned an extension leg 53 comprising a bent metal

stamping formed with a loop 54 at its end, through which I affix, by screw threading, the leveling member 41 of the character previously described. The extension leg 53 is provided with a slot 55 longitudinally along the length thereof. Through this extension leg and the strap 44 and the front strap 47, there is passed the fastening bolt 56, thus serving to dispose the extension leg 53 in any desired position. Thus the extension leg is clamped by the fastening elements 56 between the strap 44 and the front strap 47.

To each plate 49 and the inwardly turned lips 50 thereof, there is disposed the straps 57, also provided with inwardly turned lips 58 cooperating with the lips 50, previously described, to form a hinge by the pintle 59, serving to join the same. The forward ends of the straps 47, at 60, serve to hold an extension member 53a, similar in all respects to the member 53, described as associated with the leg 32a. This extension member 53a is held between the branches 60 in extensible relation by the bolts and nuts 61. In this manner, I have provided a frontal and lateral base member made of simple metal strapping material which may be bent into the desired shape by stamping operations, and the individual elements forming the entire combination shaped or stored in a knocked down condition, for purposes which will be obvious to those skilled in the art.

The features of stability, adjustability for height upon a show case, as 14, are all inherent to that embodiment previously described and illustrated in Figures 4, 5 and 6.

In the embodiment shown in Figure 10, I may omit the back plate 17 and substitute therefor an additional leg, such as 33b. This is a substantial duplicate of the assembly forming the leg 33a and I need only substitute for the plate 17a duplicates thereof comprising the plates 49 and the hinged assembly attached thereto comprising the leg 33a and herein referred to as 33b.

Although I have described the extension legs 33a and 33b as preferably hingedly connected to the plates 49, I may retain the desirable features of extensibility and stability obtained by these legs, as well as that of aligning the standard upon an uneven supporting surface, such as the show case, by making the straps forming the legs 33a and 33b integral with the plates 49 and for purposes of assembly or taking down for shipment, provide these members with the parts forming the plates 49 forming members in the nature of angle pieces.

In general, I have thus provided a display stand and mounting means therefor whereby the same may be assembled upon any supporting surface quickly and efficiently, particularly in connection with a show case, without detracting from the general appear-

5
ance thereof, and without materially modifying the same to affix it rigidly and efficiently in position. Thus I am enabled to increase the display area of a show case and enhance its general appearance without obstructing the vision of a sales clerk normally positioned behind the show case, which may be used for a counter or the like.

10 Furthermore, I have provided a display element which may be associated with a show case and where the same includes glass construction and glass top, the display element may be affixed thereon quickly and efficiently with stability for all purposes required by change of the character and size 15 of the display area, without modification or special preparation of the supporting area.

20 Having thus described my invention and illustrated its use, what I claim as new and desire to secure by Letters Patent, is—

25 1. In a display device, a standard arranged to mount display elements or brackets independently, a support therefor adapted to vertically dispose said standard upon a show case or the like, comprising complementary sections arranged to embrace the base of said standard, one of said sections comprising an extension plate including means to fasten said plate to the show case.

30 2. In a display device, a standard arranged to mount display elements or brackets independent, a support therefor adapted to vertically dispose said standard upon a show case or the like, comprising complementary sections arranged to embrace the base of said standard, one of said sections comprising an extension plate including means to fasten said plate to the show case, said plate being channelled to receive said standard.

35 3. In a display device, a standard arranged to mount display elements or brackets independently, a support therefor adapted to vertically dispose said standard upon a show case or the like, comprising complementary sections arranged to embrace the base of said standard, one of said sections comprising an extension plate including means to fasten said plate to the show case, said sections having slideable engaging portions whereby one may be offset from the other.

40 4. In a display device, a standard arranged to mount display elements or brackets independently, a support therefor adapted to vertically dispose said standard upon a show case or the like, comprising complementary sections arranged to embrace the base of said standard, one of said sections comprising an extension plate including means to fasten said plate to the show case, said plate being channelled to receive said standard and means for positioning a fastening element 45 in various positions formed on said plate

whereby the plate may be attached along various heights on said show case.

5. In a display device, a standard arranged to mount display elements or brackets independently, a support therefor adapted to vertically dispose said standard upon a show case counter or the like, said support comprising a complementary front section and back section, each of said sections being channelled to comprise the general cross sectional contour of said standard, one section comprising a plate having lateral disposed members including means to fasten the same to the show case, and a variable slot and pin engagement between said plate and front section.

6. In a display device including a standard arranged to mount a display element or bracket, a support therefor, comprising complementary readily disengageable and adjustable front and back sections formed to comprise the general contour of said standard, one of said sections comprising an extension plate arranged to engage a side of a counter or show case and including means to fasten the same adjustably to the show case, the other of said sections including substantial lateral and frontal stabilizing legs.

7. In a display device including a standard arranged to mount a display element or bracket, a support therefor, comprising complementary front and back sections formed to comprise the general contour of said standard, one of said sections comprising a plate arranged to engage a side of a counter or show case, the other of said sections including substantial lateral and frontal stabilizing legs, and leveling means included by said legs to vary the position of said display device and for leveling the same.

8. In a display device including a standard arranged to mount a display element or bracket, a support therefor, comprising complementary front and back sections formed to comprise the general contour of said standard, one of said sections comprising a plate arranged to engage a side of a counter or show case, the other of said sections including substantial lateral and frontal stabilizing legs, and extensible members included by said legs.

9. In a display device including a standard arranged to mount a display element or bracket, a support therefor, comprising complementary front and back sections formed to comprise the general contour of said standard, one of said sections comprising a plate arranged to engage a side of a counter or show case, the other of said sections including substantial lateral and frontal stabilizing legs, formed of spaced plates, spacers for said plates and extension members disposed between said plates, whereby the stability of said support may be varied,

and fastening means for said plates, spacers and extension members.

10. In a display device including a standard arranged to mount a display element or bracket, a support therefor, comprising complementary front and back sections formed to comprise the general contour of said standard, one of said sections comprising a plate arranged to engage a side of a counter or show case, the other of said sections including substantial lateral and frontal stabilizing legs, said lateral legs being formed of spaced plates, spacers for said plates and extension members disposed between said plates whereby the stability of said support may be varied, and fastening means for said plates, spacers and extension members, said frontal legs including spaced additional plates, angularly disposed from plates forming the lateral legs.

11. In a display device including a standard arranged to mount a display element or bracket, a support therefor, comprising complementary front and back sections formed to comprise the general contour of said standard, one of said sections comprising a plate arranged to engage a side of a counter or show case, the other of said sections including substantial lateral and frontal stabilizing legs, formed of spaced plates, spacers for said plates including angle extensions serving to embrace the standard and extension members disposed between said plates, whereby the stability of said support may be varied, and fastening means for said plates, spacers and extension members.

In witness whereof I have hereunto signed my name this 2nd day of February, 1929.

MATTHEW M. FRIEDEMANN.
